PRESSER FOOT MECHANISM FOR SEWING MACHINES

Original Filed March 6, 1922 2 Sheets-Sheet 2

UNITED STATES PATENT OFFICE.

WALTER PEARSON, OF WHITMAN, MASSACHUSETTS.

PRESSER-FOOT MECHANISM FOR SEWING MACHINES.

Original application filed March 6, 1922, Serial No. 541,494. Divided and this application filed May 24, 1923. Serial No. 641,243.

To all whom it may concern:

Be it known that I, WALTER PEARSON, a citizen of the United States of America, and a resident of Whitman, in the county of 55
5 Plymouth and State of Massachusetts, have invented certain new and useful Improvements in Presser-Foot Mechanism for Sewing Machines, of which the following is a specification.

10 This invention relates to sewing machines and particularly to the presser foot mechanisms therefor, the object of the invention being to provide a mechanism of this character which will be effective in operation and 15 which will be automatically regulated in accordance with the various thicknesses of the work being operated upon.

The invention consists in certain novel features of construction and arrangement 20 of parts which will be understood readily by the description of the drawings and to the claims to be hereinafter given.

For the purpose of illustrating the invention, one preferred form thereof is shown 25 in the drawings, this form having been found to give satisfactory and reliable results, although it is to be understood that the various instrumentalities of which the invention consists can be variously arranged 30 and organized, and that the invention is not limited to the precise arrangement and organization of the instrumentalities as herein shown and described, except as required by the scope of the appended claims.

35 Of the drawings:

Figure 1 represents a side elevation of a sewing machine embodying the principles of the present invention, the casing cover being shown removed.

40 Figure 2 represents a vertical section of a portion of the front of the machine.

Figure 3 represents a horizontal section of same on line 3, 3 on Fig. 1.

45 Figure 4 represents a transverse vertical section of same on line 4, 4 on Fig. 1, and

Figure 5 represents a front elevation of a portion of the machine.

50 Similar character indicate like parts throughout the several figures of the drawings.

In the drawings, 38 is a casing for a sewing machine such as is shown and described

in another application of mine of which this application is a division, said parent application having been filed March 6, 1922, and 55 numbered 541,494.

In suitable bearings in the casing 38 is mounted a revoluble driving shaft 42 adapted to be driven by the pulley 41 when frictionally connected to the hand wheel 43 secured to the outer end of said shaft 42.

The inner end of said shaft 42 has secured thereto a cam member 47* which is provided with a peripheral cam path 48 in which is positioned a roller 98 revolubly 65 mounted on the upper end of the lever 97 secured to an oscillating shaft 96.

Fixedly secured in the casing 38 is a stud 67 having loosely mounted thereon the hub 68 of a lever 69, the front end of which is 70 pivotally connected to a link 70, the lower end of which is pivotally connected to a collar 71 secured to the presser foot bar 72.

The hub 68 is threaded and has threaded thereto the nut 73 having a plurality of depressions in one face by which it may be adjusted on said hub.

This nut 73 is cylindrical and is surrounded by the split hub 74 of an arm 75, the outer end of which is connected by a 80 spring 76 to an arm 76* pivotally mounted on a short shaft 77 adapted to oscillate in a bearing in an arm 78 pivoted at 79 to the outside of the casing 38.

This arm 78 has a slot therein through 85 which a stud 81 extends into the casing 38 and limits the movement of said arm 78 about its pivot 79.

When the arm 78 is moved about its pivot 79 the shaft 77 will be raised and lowered 90 in a slot formed in the wall of the casing 38.

The front end of the arm 78 extends over in front of the casing 38 as at 82 and has a forward extension 83 having a cylindrical depression 84 therein in which is mounted a ball 85 having oppositely disposed trunnions extending therefrom which extend through the ears 86 of a link 87, the lower end of which is pivotally connected at 88 to an arm 89 pivoted at 90 to a lug on the casing 38. 100 The free end of the arm 89 has pivotally mounted thereon a block 91 adapted to travel in a curved slot 92 in a link 93, the upper end of which is pivotally connected at

94 to the free end of an oscillating lever 95 secured to the front end of the oscillating shaft 96 mounted in bearings in the front wall of the casing 38 and in a boss 96^x extending inwardly from one wall of said casing 38.

The slotted link 93 is provided with a plurality of indicating characters 100 with which coacts a pointer 101 on the free end 10 of the arm 89.

By moving the arm 89 about its pivot 90 and registering the pointer 101 with any predetermined indicating character, the fulcrum 102 of said link 93 will be varied 15 at will.

The lower end 103 of the link 93 is adapted to be connected with the feed mechanism as will be hereinafter described.

The short shaft 77 has secured to its inner end an arm 104 projecting toward the front of the casing 38 and this arm 104 has pivotally mounted in its upper face a block 105 having a cushion of leather 106 secured to its upper face. This member has a concentric slot 107 therein through which extends a holding screw 108. The block 105 is adapted to freely move about its center to vary the inclination of the pad 106 as will be hereinafter described.

30 The hub of the arm 76^x has a lug 109 extending forwardly therefrom in which is mounted the adjustable screw 110 with its head in contact with the lateral lug 111 on said arm 104. Through this connection 109 the action of the spring 76 is transmitted to the arm 104.

The split hub 74 is limited in its movement about the axis of the threaded hub 58 by means of the adjusting screw 112, the end 40 of which bears against the flat upper face 113 thereof.

This split hub 74 is provided with an adjusting screw 114 extending through the ears 115 thereof, thus providing a means for 45 creating a desired degree of friction between said hub 74 and the cylindrical nut 73.

The presser foot bar 72 reciprocates in bearings 126, 127 in the walls of casing 38 and its upper end is reduced in diameter and 50 threaded as at 128 to receive the nuts 129 between which and the upper wall of the casing is a resilient washer 130 to take up any shocks during the downward movement of said bar 72. This downward movement 55 of the bar 72 is imparted by a helical spring 131 surrounding the upper end of the bar 72 between the upper wall of casing 38 and a collar 132 secured to said bar 72 by means of a set screw 133.

60 Below the collar 132 is the collar 71 secured thereto by a set screw 135 and pivotally connected to the lower end of the link 70, the upper end of which is pivotally connected to an arm 69 formed upon the threaded hub 68 as previously described.

Pivoted at 136 to the casing 38 is a manually actuated lever 137 having a finger 138 extending into the interior of the casing and bearing against the under face of the collar 71 on the presser foot bar 72. 70

By means of this lever 137 the presser foot may be lifted from the work when it is desired to remove the work from the horn or insert new work thereon.

The lower end of the presser foot bar 72 75 has formed thereon or secured thereto a block 153, one side of which is provided with a groove 154 (see Fig. 2) in which is mounted the upper forked end of a lever 155, to the lower end of which is rigidly 80 connected the work feeding member 156, having a work engaging finger 157 secured in the lower end thereof.

The block 153 has a pin 158 projecting across the slot 154 and positioned in the 85 forked end of the lever 155, thereby forming a fulcrum therefor.

The member 156 is connected by a spring 159 at 160 with the lower end of the extension 103 of the curved link 93. 90

The lower end of the block 153 has an arm 161 extending downwardly toward the needle 129 and has mounted therein the presser foot 162.

Secured to and on opposite sides of the 95 block 153 are two cam plates 164, each having a cam slot 165 formed therein through which extends the pin 166 connecting the lever 155 with the upper end of the work feeding member 156.

This pin 166 is pivotally connected to one end of a link 167, the opposite end of which is pivotally connected at 168 to the extension 103 of the link 93.

Between the inner wall of the casing 38 105 and the cylindrical nut 73 is a lever 170 having a roller 171 on its free end positioned in the cam path 172 of the cam 47.

The opposite end of the lever 170 is provided with a threaded boss 173 mounted 110 upon the threaded hub 68 closely adjacent to the nut 73.

When the lever 170 is moved about the axis of the stud 67 by means of the throw in the cam 172, the first action will be to turn the hub 115 173 upon the threaded hub 68 thereby forcing it into such frictional contact with the nut 73 that said nut will be caused to rotate about the axis of said stud 67 during the continuation of the movement of said lever. 120

As the said nut is mounted upon the threaded hub 68 of lever 69 it is obvious that the hub 68 will be rotated with said nut 73 thereby causing the outer end of lever 69 to be moved upwardly by the continued 125 movement of the lever 170.

This upward movement of the free end of lever 69 will cause the presser foot 72 to be lifted and at the same time the movement of the nut 73 will cause the spring 76 130

to be expanded and create more tension therein, thus causing a resistance to the movement of the friction nut 73.

This is accomplished by means of the extension 174 bearing upon the upper end of the block 153 at the lower end of the presser foot bar 72.

The action is as follows:—The parts being in the position shown in Figs. 1 and 2, assume that a piece of work of a certain thickness is introduced beneath the presser foot, the bar 72 will descend thereon under pressure of spring 131, the link 70 will cause the arm 69 to assume a relative position, the hub 68 turning in the nut 73, the latter being held from revolving by the spring 76 acting on the arm 75 of the collar 74, holding the collar stop 113 against the set screw 112 and the collar gripping the nut 73. Thus the presser foot may adjust itself to the thickness of the work without disturbance of or hindrance from the nut 73, and the nut 73 retains its position relative to the boss 173 of lever 170, because, in turning, the hub 68 turns equally in the nut and the boss. When the boss 173 is revolved on the hub by the action of cam 172 it is screwed against the nut, (the latter having been suitably adjusted in proximity to the boss 173) and the boss and nut enter into combined action as lock nuts, thus engaging upon and turning the hub 68. The movement of the hub 68 and consequently the lift given to the presser foot from the work is thus the same whatever the thickness of the work, and the presser foot is free to adjust itself automatically to the thickness of the work.

The part 104, being lifted when the presser foot bar rises, puts extra tension on the spring 76 which assists in maintaining the nut 73 and boss 173 locked together as the arm 69 rises to lift the presser bar. Since the work feed is carried by the presser foot it also takes such position as corresponds to the thickness of the work.

When the lever 170 returns to its normal position, it will remove the hub 173 thereof from contact with the nut 73 and permit it to return to its normal position.

It will be noted that the block 153 on the lower end of the presser foot bar carries with it the work feeding member 156 which is provided with means whereby it may be moved about a fulcrum pin 158 extending transversely of said block 153 and whereby it may also be moved lengthwise of the presser foot bar 72.

It will be further noted that said block 153 also has mounted thereon the plates 164 provided with cam slots 165 which control the movement of the work feeding member 156 when actuated by the oscillating lever 83 through the medium of the link 167.

The work feeding point 157 in the lower end of the work feeding member 156 is normally retained in the position indicated in Fig. 5 by the spring 159, in which position the presser foot 162 is permitted to act upon the work while the work feeding point 157 is removed from contact with said work.

The construction of presser foot mechanism herein shown and described is very effective in operation.

It is believed that the operation and many advantages of the invention will be understood readily without further description.

Having thus described my invention, I claim:

1. In a machine of the class described a presser foot bar, a revoluble cam; a fixed stud; an exteriorly threaded hub loosely mounted on said stud and having a radial arm linked to the presser foot bar; a cylindrical nut on said threaded hub; and a lever actuated by said cam and threaded on said hub for causing it to be brought into frictional contact with said nut to rotate the hub.

2. In a machine of the class described a presser foot bar, a revoluble cam; a fixed stud; an exteriorly threaded hub loosely mounted on said stud and having a radial arm linked to the presser foot bar; a cylindrical nut on said threaded hub; a lever actuated by said cam and threaded on said hub for causing it to be brought into frictional contact with said nut to rotate the hub; and a spring controlling the movement of said arm.

3. In a machine of the class described, a presser foot bar; a revoluble cam; a fixed stud; an exteriorly threaded hub loosely mounted on said stud and having a radial arm linked to the presser foot bar; a cylindrical nut on said threaded hub; a friction collar on said cylindrical nut; a lever actuated by said cam and threaded on said hub for causing it to be brought into frictional contact with said nut to rotate the hub; and means for controlling the friction between said collar and nut.

4. In a machine of the class described, a presser foot bar; a revoluble cam; a fixed stud; an exteriorly threaded hub loosely mounted on said stud and having a radial arm linked to the presser foot bar; a cylindrical nut on said threaded hub; a friction collar on said cylindrical nut provided with a radial arm; a lever actuated by said cam and threaded on said hub for causing it to be brought into frictional contact with said nut to rotate the hub; a block near the lower end of the presser foot bar; an oscillating member the end of which rests on said presser foot block; and a spring between the arm of the friction collar and said oscillating member.

5. In a machine of the class described a

- presser foot bar, a revoluble cam; a fixed stud; an exteriorly threaded hub loosely mounted on said stud and having a radial arm linked to the presser foot bar, said bar having a groove in its lower end; a cylindrical nut on said threaded hub; a lever actuated by said cam and threaded on said hub for causing it to be brought into frictional contact with said nut to rotate the hub; a work feeding member in said groove; a fulcrum therefor; and means for moving said work feeding member about its fulcrum.
6. In a machine of the class described a presser foot bar, a revoluble cam; a fixed stud; an exteriorly threaded hub loosely mounted on said stud and having a radial arm linked to the presser foot bar, said bar having a groove in its lower end; a cylindrical nut on said threaded hub; a lever actuated by said cam and threaded on said hub for causing it to be brought into frictional contact with said nut to rotate the hub; a work feeding member in said groove; a fulcrum therefor; and means for controlling the movement of said work feeding member about its fulcrum as well as for moving it endwise of said bar.
7. In a machine of the class described a presser foot bar, a revoluble cam; a fixed stud; an exteriorly threaded hub loosely mounted on said stud and having a radial arm linked to the presser foot bar, said bar having a groove in its lower end; a cylindrical nut on said threaded hub; a lever actuated by said cam and threaded on said hub for causing it to be brought into frictional contact with said nut to rotate the hub; a work feeding member in said groove; a fulcrum therefor; a plate carried by said presser foot bar having a cam slot coacting with a projection on the work feeding member to control the movement of said work feeding member about its fulcrum and endwise of said bar.
8. In a machine of the class described a presser foot bar, a revoluble cam; a fixed stud; an exteriorly threaded hub loosely mounted on said stud and having a radial arm linked to the presser foot bar, said bar having a groove extending longitudinally of its lower end; a cylindrical nut on said threaded hub; a lever actuated by said cam and threaded on said hub for causing it to be brought into frictional contact with said nut to rotate the hub; a pin extending transversely of said groove; a work feeding member having a forked upper end in said groove and straddling said pin; means for moving said work feeding member about the axis of said pin; and means carried by the presser foot for controlling the movement of said work feeding member about said pin and endwise of said groove.
- 65 9. In a machine of the class described a presser foot bar, a revoluble cam; a fixed stud; an exteriorly threaded hub loosely mounted on said stud and having a radial arm linked to the presser foot bar; a cylindrical nut on said threaded hub; a lever actuated by said cam and threaded on said hub for causing it to be brought into frictional contact with said nut to rotate the hub; a block near the lower end of said presser foot bar; a two part oscillating member, the end of which rests on said presser foot block; and means for adjusting the two parts of said oscillating member relatively to each other.
10. In a machine of the class described a presser foot bar, a revoluble cam; a fixed stud; an exteriorly threaded hub loosely mounted on said stud and having a radial arm linked to the presser foot bar; a cylindrical nut on said threaded hub; a lever actuated by said cam and threaded on said hub for causing it to be brought into frictional contact with said nut to rotate the hub; a block near the lower end of said presser foot bar; a short oscillating shaft; a member secured thereto and oscillating therewith, the end of which rests on said presser foot block; a lever loosely mounted on said short shaft and having two arms; a spring between one arm and the arm on said collar; and an adjustable member in the other arm bearing against a lug on said oscillating member.
11. In a machine of the class described, a revoluble cam; a fixed stud; a threaded hub loosely mounted thereon and having a radial arm; a presser foot bar; a collar thereon; a link between said arm and collar; a cylindrical nut threaded to said hub; a cam lever having a boss threaded to said hub and adapted to be moved into frictional contact with said nut; a friction collar surrounding said nut and having an arm extending therefrom; means for regulating the friction between said collar and nut; a block on the lower end of said presser foot bar; a two-part oscillating member, the end of which rests on said presser foot block; a spring between said arm and oscillating member; and means for adjusting the two parts of said oscillating member relatively to each other.
12. In a machine of the class described, a revoluble cam; a fixed stud; a threaded hub loosely mounted thereon and having a radial arm; a presser foot bar; a collar thereon; a link between said arm and collar; a cylindrical nut threaded to said hub; a cam lever having a boss threaded to said hub and adapted to be moved into frictional contact with said nut; a friction collar surrounding said nut and having an arm extending therefrom; means for regulating the friction between said collar and nut; a block on the lower end of said presser foot bar; a short

oscillating shaft; a member secured thereto and oscillating therewith, the end of which rests on said presser foot block; a lever loosely mounted on said short shaft and having two arms; a spring between one arm and the arm on said collar; and an adjustable member in the other arm bearing against a lug on said oscillating member.

13. In a machine of the class described, a revolute cam; a fixed stud; a threaded hub loosely mounted thereon and having a radial arm; a presser foot bar; a collar thereon; a link between said arm and collar; a cylindrical nut threaded to said hub; a cam lever having a boss threaded to said hub and adapted to be moved into frictional contact with said nut; a friction collar surrounding said nut and having an arm extending there-

from; means for regulating the friction between said collar and nut; a block on the lower end of said presser foot bar; a short oscillating shaft; a movable member carrying said short shaft; a member secured to said short shaft and oscillating therewith, the end of which rests on said presser foot block; a lever loosely mounted on said short shaft and having two arms; a spring between one arm and the arm on said collar; and an adjustable member in the other arm bearing against a lug on said oscillating member.

Signed by me at Whitman, Mass., this 22nd day of May, 1923.

WALTER PEARSON.

Witness:

VIRGINIA M. PEARSON.
